UNITED STATES PATENT OFFICE.

THOMAS O. PERRY, OF OAK PARK, ILLINOIS.

VACUUM HEATING SYSTEM.

1,364,139.

Specification of Letters Patent.

Patented Jan. 4, 1921.

Application filed April 2, 1917. Serial No. 169,299.

To all whom it may concern:

Be it known that I, THOMAS O. PERRY, a citizen of the United States, residing at Oak Park, in the county of Cook and State of Illinois, have invented new and useful Vacuum Heating Systems, of which the following is a specification.

My invention relates to improvements in vacuum heating systems in which steam is supplied to radiators through piping connected to a boiler and the water of condensation is returned to the boiler or is discharged through thermo-valves; and the objects of my improvements are, first, to provide for effectually removing air from the radiators; second, to provide for returning condensed steam to the boiler freed from air and without undue waste of heat; third, to provide against back-leakage of air through the vacuum producing mechanism; and, fourth, to effect the return to the boiler of condensed steam without requiring the use of a separate pump in addition to the vacuum producing device.

I attain these objects by the mechanism illustrated in the accompanying drawing, in which—

Figure 1 is a diagrammatic outline of the entire vacuum heating system; Fig. 2, a sectional plan of the vacuum producer; and Fig. 3, a vertical section of the vacuum producer.

Similar numerals refer to similar parts throughout the several views.

The boiler 1 supplies steam to the radiator 2 through the pipes 3 and inlet valve 4. Water of condensation flows or is conducted back to the boiler through a thermo-valve 5, pipes 6, vacuum tank 7, pipes 8, tank 9 and pipes 10. The pipe 11 and trap 12 allow water of condensation in pipe 8 to reenter the boiler without returning steam. The general arrangement so far described is the usual one adopted by so called return pipe steam heating systems. That is, the parts named are all used with such systems and some other parts as well which my invention renders unnecessary.

A leading feature of all return-pipe vacuum steam heating systems is the thermo valve 5, which allows water and air to escape from a radiator without permitting the passage of steam, and some form of vacuum pump is used to draw water and air from the return pipe 6. The vacuum tank is not a necessity but is intended to greatly in-

crease the vacuum space so that the vacuum pump need not operate continuously.

The vacuum producer 9 is the distinctive feature of my invention. The vacuum producer, in so far as pertains to vacuum production only, is shown in Patent No. 1,071,789, issued to myself Sept. 2, 1913 for hydro-turbine aspirator. My present invention relates to the adaptation of submerged aspirators to vacuum steam heating systems.

A tank 9 closed against free escape of air is partially filled with water whose surface is indicated by the broken line 13. Submerged in the water are two superposed disks 14 adapted to revolve about a vertical axis and having their intervening space free from obstruction except for two opposite impellers 15 which connect together the two disks and divide the space between into two equal parts. These impellers extend to the outer periphery of the disks but do not meet at the center. Screwed into the lower disk from below is a tubular journal 16 which communicates centrally with the space between the disks. Screwed into the upper disk is a shaft 17 extending upward and having a reduced extension 18 which passes through a packing gland 19 in the tank cover 20. A clutch 21 serves for making direct connection with the shaft of a vertical electric motor 22 by which the disks 14 are made to revolve rapidly in the water. The gland cap 23 has a cup-shaped top suitable for retaining oil. The motor rests on the tank cover as shown.

The water in the tank is held from whirling by means of stationary water brakes 24 which extend upward from a supporting 95 brake plate 25 secured to the bottom of the tank by the studs 26 which also secure underneath the tank a circular flange 27 making therewith a water-tight joint. The flange 27 is threaded to receive the terminal end of pipe 8 directly below the tubular journal 16 which revolves within a close bearing 28, lined with wood or other suitable material, and clamped between the brake-plate and flange 27.

Any water which enters the space between the disks 14 from the return pipe 8, or otherwise, is immediately discharged into the tank by centrifugal force, but air and vapor which are too light for centrifugal discharge are whirled between the disks and drawn into the water by entrainment producing

a strong partial vacuum in the pipe 8 as described in the patent above mentioned. The air rises in bubbles through the water and accumulates in the top of the closed tank 5 producing pressure on the surface of the water. Accumulation of water of condensation tends to raise the water surface 13 above the open lower end of the discharge pipe 10 until the accumulating air pressure above 10 drives the excess of water into the boiler 1, past the check valve 29.

To prevent air from entering the discharge pipe 10, a float 30, inclosed in a separate float-chamber 31, located just outside of the 15 tank may be used to open a vent valve 32 before the water surface is lowered sufficiently to uncover the lower end of the discharge pipe. As the top of the float chamber communicates with the top of the tank 20 through the nipple 33, and the bottom of the float chamber receives water from the bottom of the tank through the pipe 34, the water level in tank and float chamber will be the same and the float will act the same 25 as if it were located within the tank. The float has a seating guide 35 just beneath the vent and at the lower end is guided by a stem 36 extending loosely through the bottom of the float chamber. As water must enter and 30 find its way out through the restricted opening around the stem 36, agitation of the water within the float chamber is prevented. If water were discharged through the pipe 10 into a separating tank in the usual manner, 35 the float 30 could be dispensed with, as both water and air would then be discharged through the same pipe.

The apparatus as so far described is complete for use under ordinary circumstances 40 if the thermo valves on the radiators effectively prevent passage of steam into the return pipe 8, as they are supposed to do; but as these valves are liable to leak and pass considerable steam it is sometimes less trouble 45 to condense this steam than spend too much time in cleaning the valves. Therefore I have provided a condensing device, attached to the return pipe, which will supply the necessary cold condensing water, as 50 much as may be needed and no more.

The pipe 37 connects with a source of cold water and communicates with the return pipe 8 through the nipple 38 when the passage is not closed by the valve 39 which is 55 mounted on a cylindrical stem 40 passing through a packing gland 41 in the connecting T 42. The cylindrical stem has a collar 43 thrust upward by a helical spring 44 tending to hold the valve 39 open. The lower end 60 of the spring rests upon a casing 45 inclosing a flexible diaphragm and connected with the T by a tubular support 46 which encloses the spring. The diaphragm 47 connects with the stem 40 in a manner suitable 65 for compressing the spring and closing the

valve 39 by suction underneath the diaphragm whenever the desired vacuum tension is maintained in the return pipe 8. The part of the casing 45 below the diaphragm communicates with the pipe 8 through pipe 70 48. If too much steam leaks past the thermo valves 5, the vacuum in the return pipe 8 will be impaired causing the cold water valve 39 to open. If the thermo valves do their duty and prevent steam from entering the 75 pipe 8, the desired vacuum will be maintained without condensing water sufficiently to keep the cold water valve closed, so that no water will be wasted for condensing when not needed. However, as much cold water 80 can be used without wastefulness as may be required to replenish unavoidable loss from the boiler. An automatic switch 49 adapted to stop the motor whenever the vacuum tension reaches the desired maximum limit, and 85 start it when the vacuum is reduced to a predetermined minimum, is connected by the pipe 50 with the expansion tank 7.

The cold condensing water may be conducted directly into the tank 9 through the 90 pipe 38 instead of being drawn there by suction through the return pipe 8. If the water in the tank is by any means maintained at a temperature well below the boiling point, all steam will be immediately condensed as it issues from between the disks 14 and rises through the water in fine bubbles.

This vacuum producer is especially adapted to use with steam vacuum heating systems because the water in the tank at all times effectively seals the return pipe against leakage of air back into the radiators after it has once been sucked out. Ordinary vacuum pumps, especially when idle, are not 105 well adapted to exclude the return of air to the system and consequently have to be kept in operation more than would otherwise be necessary. Water, too, is detrimental to most vacuum pumps which usually are protected against the condensed steam by a 110 rather elaborate water and dirt trap.

This vacuum producer, instead of being injured by condensation, depends for its action upon submergence, and the water condensed from steam helps by maintaining the supply against waste. That dirt can not act injuriously is also obvious, and dirt screens, such as others use, are entirely unnecessary for protecting the aspirator, as is fully set 120 forth in my previous patent referred to above.

The packing gland 19 should fit the shaft 18 closely enough to prevent much leakage of water but does not need to be air-tight. 125 The air which accumulates in the top of the tank might all be allowed to escape by leakage around the shaft, or otherwise, instead of being released by a float-controlled vent, or by discharge with the water through the 130

pipe 10. If a small amount of water also leaks past the gland it may be returned to the boiler by other means or may go to waste.

6 As usually installed, the pump is primarily adapted to pumping water and incidentally pumps air mingled with water; whereas, the submerged aspirator here described does not necessarily pump water at 10 all, and what water passes through incidentally in no way aids the extraction of air from the return pipe. If the water of condensation be admitted to the closed tank without passing through the aspirator, the 15 air is more effectively forced into the tank through the water of submergence.

During those intervals when the aspirator is in action, water can not flow back into the return pipe. When the aspirator is not 20 in action, a limited amount of water flows back into the return pipe and forms an impervious seal against reentrance of air into the system through the return pipe. In other systems, air can leak back through the 25 pump during periods of inaction, as dependence is placed upon check valves past which most of the air leaks which has to be pumped and repumped. If all back leakage of air could be prevented, there would be little 30 need of a vacuum pump after the air has once been pumped out.

Claims:

1. In a vacuum heating system, the combination with the boiler, the radiators and the 35 return pipe, of a tank for receiving the contents of said return pipe, a water exit located some distance above the tank-bottom, a discharge pipe leading from said water exit to said boiler, a check valve to prevent 40 return of water from said discharge pipe, an aspirator submerged in the water retained in the lower part of said tank, a motor for actuating said aspirator, tubular connection between said return pipe and said aspirator, 45 an air vent located higher up than said water exit and means for closing said vent when water accumulates above said water exit, whereby a water level is maintained sufficient to constantly submerge the water exit, 50 substantially as herein set forth.

2. In a vacuum heating system, the combination with the boiler, the radiators and the return pipe, of a tank for receiving the contents of said return pipe, a water exit located some distance above the tank-bottom, a discharge pipe leading from said water exit to said boiler, a check valve to prevent 55 return of water from said discharge pipe, an aspirator submerged in the water retained in the lower part of said tank, a motor for actuating said aspirator, tubular connection 60

between said return pipe and said aspirator, an air vent located higher up than said water exit and means whereby changes in water level above said water exit close or open said 65 vent as required to maintain a proper depth of water, substantially as herein set forth.

3. In a vacuum heating system, the combination with the boiler, the radiators and the return pipe, of a tank for receiving the contents of said return pipe, a water exit located some distance above the tank-bottom, a discharge pipe leading from said exit to said boiler, a check valve to prevent return of water from said discharge pipe, an aspirator submerged in the water retained in the lower part of said tank, a motor for actuating said aspirator, tubular connection between said return pipe and said aspirator, an air vent normally open at a higher level 80 than said water exit, and means for closing said air vent when excess of water accumulates above said water exit, whereby further accumulation of air expels said excess of water, substantially as herein set forth. 85

4. In a vacuum heating system, the combination with the boiler, the radiators and the return pipe, of a tank for receiving the contents of said return pipe, a water exit located some distance above the tank-bottom, 90 a discharge pipe leading from said water exit to said boiler, a check valve to prevent return of water from said discharge pipe, an aspirator submerged in the water retained in the lower part of said tank, a motor for actuating said aspirator, tubular connection between said return pipe and said aspirator, a vent for escape of air from said tank, a float for opening and closing said vent and a separate float chamber having a 100 restricted water inlet passage, substantially as herein set forth.

5. In a vacuum heating system, the combination with the boiler, the radiators and the return pipe, of a covered tank for receiving the contents of said return pipe, a water exit intermediately placed between the bottom and top of said tank, an aspirator in the water retained in the lower part of said tank, tubular connection between 110 said aspirator and said return pipe, a motor for actuating said aspirator, a discharge pipe leading from said water exit, an air vent located higher up than said water exit and means whereby accumulations of water 115 above said water exit act to restrict escape of air through said vent, substantially as herein set forth.
